Inventor:

Jno. Farnsworth

UNITED STATES PATENT OFFICE.

JONAS FARNSWORTH, OF LEWISTON, MAINE.

IMPROVED WINDOW-WASHER.

Specification forming part of Letters Patent No: 35,090, dated April 29, 1862.

To all whom it may concern:

Be it known that I, JONAS FARNSWORTH, of Lewiston, in the county of Androscoggin and State of Maine, have invented a new and useful Improvement in Window-Washers; and I do hereby declare that the same is fully described in the following specification and accompanying drawings, letters, figures, and references thereof.

Of the said drawings, Figure 1 represents a view of one side of my window-washer. Fig. 2 is a view of the opposite side. Fig. 3 is a view of one end. Fig. 4 represents the window-washer as turned up to show the narrow edge of it. Fig. 5 is a central and longitudinal section of the same. Fig. 6 is a detached view of the piston.

The nature of my invention consists in the peculiar arrangement and combination of a sponge to moisten the window, a rubber to rub up the dirt, and a syringe to rinse it down, by the use of which I am enabled to wash windows, carriages, &c., with the least possible amount of labor and water. One pail of water will do as much as four used in the ordinary way.

A denotes the piston; B, the cylinder; D, the washer-head; E, the sponge; F, the rub-

ber. The sponge is held in place by the clamp G and screws H H. The rubber is held in place by the clamp I and screws J J.

K is the orifice or aperture through which the water is forced. This aperture may consist of one or more holes, either round or flat, and the sponge may be substituted by a brush, cloth, or other porous substance, and the rubber may be substituted by leather, cork, or other soft pliable substance; or the rubber may be left off and the washing may all be done with the sponge and syringe. Such, in fact, would constitute the peculiar essence of my invention; but I prefer to use it as above described; therefore

What I claim as my invention, and desire to secure by Letters Patent, is—

The combination and arrangement of the piston A, the cylinder B, the head D, with sponge E, and rubber F, substantially as and for the purpose specified.

In testimony whereof I have hereto set my signature this 11th day of March, A. D. 1862.

JONAS FARNSWORTH.
